UNITED STATES PATENT OFFICE.

JOHN B. TIMBERLAKE, OF JACKSON, MICHIGAN.

HANDLE FOR DISHES.

SPECIFICATION forming part of Letters Patent No. 241,756, dated May 17, 1881.

Application filed April 2, 1881. (No model.)

To all whom it may concern:

Be it known that I, J. B. TIMBERLAKE, of Jackson, in the county of Jackson and State of Michigan, have invented certain new and useful Improvements in Detachable Handles for Dishes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improved handle for vessels of glass, earthenware, silver, or other material, the subject-matter hereof being improvements upon the devices shown in another application which was allowed me June 26, 1880. The handle portion of the device extends over the top of the vessel, and is constructed to be readily attached thereto and detached therefrom, it being held in place upon the vessel by means of its elasticity.

Figure 1 is a perspective view of a handle embodying some of my improvements. Fig. 2 is a perspective view of a modified form. Figs. 3 and 4 illustrate the combination, with the handles shown in Figs. 1 and 2, of sliding clamps. Fig. 5 illustrates another modified form with a sliding clamp. Figs. 6 and 7 show the combination, with the elastic handle, of feet or bottom supports for the vessel. Fig. 8 is a side elevation of a vessel having attached thereto a handle of the form shown in Fig. 5.

The handle is formed of one or more pieces of wire or metal, which may be circular or polygonal in cross-section. The metal of which it is formed should be as elastic as possible, so as to permit the clamping part to be readily manipulated in attaching or detaching the handle.

In Fig. 1 the handle is represented as being made of two pieces of wire bent to form the upper curved part, A, where the pieces are secured together. They may be secured by twisting the wires around each other, though other fastenings may be employed, if desired. At the bottom the wires are provided with clamping devices whereby they may be securely held in place upon the vessel. When the handle is formed as shown in said Fig. 1 the clamping

part is made by bending a portion of each wire, as shown at A' A'. Between the upper part, A, and the clamping part A' A' are situated the downwardly-extending arms A² A². These last said parts A² are arranged to have a tendency to approach each other. The elasticity that is thus brought into play is utilized to hold the handle against the vessel.

In Fig. 2 the part A is shown as being solid, and may be constructed either by soldering two wires together or by bending a single wire. The parts A' A' in this construction, shown in Fig. 2, are carried by parts A² A² corresponding to the parts A² A² in Fig. 1. These parts A² in Fig. 2 may be formed either by dividing a single wire in such manner as to provide elastic clamps at the bottom, or when two wires are soldered together at the top, by allowing them to diverge more or less toward the bottom.

If desired, with the constructions shown in Figs. 1 and 2, and above described, may be combined sliding clamps such as shown at B, whereby, after the handle has been placed upon the vessel, the diverging parts A² A² may be brought together with additional force, though under most circumstances the elasticity of the parts A² A² will serve to securely hold the handle in place.

In Fig. 5 I have shown a handle having many of the features above described, and, in addition thereto, having one of the clamping parts A' separable at one end from the other clamping part entirely. In this case the parts A' are arranged to operate by elasticity, and after the handle has been placed at the proper point they clamp it securely. A sliding clamp, B, may be also combined with a handle of this construction, if desired.

In Fig. 8 I have shown one of the methods of attaching a handle having my improvements to a vessel of a class quite common for table and other uses. Such vessels are generally formed with expanded parts or depressions, especially at or near the top or the bottom. With such vessels my improved handle can be made to very easily engage, although it is adapted, as can be readily seen, to be attached to vessels or dishes of most of the ordinary kinds.

Elastic handles of the kind which I have devised may be combined with feet or supports for the vessel, so arranged that when attached

they shall extend below the bottom thereof and support it above the table or other object upon which it is resting.

In Figs. 6 and 7 C C represent feet adapted to perform the offices last described. They are shown in Fig. 6 to be attached to the elastic handle at the bottom, which handle in this case should be secured to the vessel at as low a point as possible, in order to make the legs available.

In Fig. 7 the legs are shown as being formed of the same wires that constitute the handle portions. The lower parts, C C, shown in this figure, can be used for ornamental purposes also, for, if the clamps be engaged with the vessel at a point high enough, the legs can be suspended entirely above the table, and in this position they form very tasteful ornaments.

It will be understood that feet or legs of substantially the character described can be readily combined with handles differing more or less from the specific forms I have shown without departing from the features of my invention, which consists in arranging the feet or legs so that they shall be held in place by the elasticity of the wire above. Therefore I do not wish to be limited to the exact form of dish-support which I have shown.

What I claim is—

1. The herein-described detachable handle for vessels having the upper bent part, A, one or more downwardly-extending parts, A² A², and the clamping parts A' A', connecting the separate parts A² A² upon one side with the corresponding part of the handle upon the opposite side, substantially as set forth.

2. The herein-described detachable handle for vessels formed of two elastic wires joined together at the upper part, A, having the di-

verging parts A² A², and the connecting portions A' A', substantially as and for the purposes set forth.

3. The herein-described detachable handle for vessels having the bent substantially U-shaped part A at the top, the downwardly-extending elastic parts A² A², and the parts A', lying in planes transverse to the parts A² A², substantially as set forth.

4. The herein-described detachable handle for dishes having the bent substantially U-shaped part A, the dish-supporting parts A' A', and the spring parts A² A², in combination with the sliding clamp B, as set forth.

5. The herein-described detachable handle for dishes having the elastic parts A² A², the connecting parts A' A', for engaging with and supporting the vessel, and the upper portion A, arranged, substantially as described, to connect the downwardly-extending elastic parts A' A', as set forth.

6. The herein-described detachable support for dishes, consisting of the upper part, A, the elastic parts A², and the feet or legs C, extending below the vessel and attached to the elastic parts A', which clamp them in place upon the vessel, as set forth.

7. The herein-described detachable support for vessels, it consisting of legs or projections adapted to be extended below the vessel and to be clamped against it by means of elasticity, substantially as and for the purpose set forth.

In testimony that I claim the foregoing I have hereunto set my hand.

JOHN B. TIMBERLAKE.
